MARKING DEVICE

Albert L. Lundquist, Port Arthur, Tex.

Application March 21, 1939, Serial No. 263,295

6 Claims. (Cl. 91—12)

The present invention relates to a marking device and more particularly to an improved marker of the character adapted to mark a guide line or stripe upon the surface of a road, pavement or the like.

The primary object of the invention resides in the provision of a marking device capable of travel over the surface of a road, pavement or the like by an improved form of traction means, which means is readily adjustable for varying the width of the mark or stripe to be painted upon the road surface.

A further object of the invention resides in the provision of a road marker embodying traction means supported upon a pair of spaced shafts mounted in a frame and comprising a pair of inner and outer tread carrying members supported on the shafts in adjusted relation and having rollers mounted in spaced relation around their peripheries, with an endless rubber tread member frictionally engaging the rollers between each pair of spaced members, and a suitable spray mechanism arranged to deliver a spray of paint upon the surface of the road between the pair of tread carrying members. The tread carrying members are adjustably supported on the shafts whereby the space therebetween can be varied for permitting the spraying of traffic stripes or marks of various widths on road surfaces, pavements and the like.

The invention will be fully and comprehensively understood from a consideration of the following detailed description when read in connection with the accompanying drawings which form a part of the application.

In the drawings:

Figure 1 is a side elevational view of a marking device embodying the features of the present invention.

Figure 2 is a side elevational view of the device illustrated in Figure 1 with the spraying mechanism detached therefrom.

Figure 3 is a top plan view of the construction shown in Figure 2.

Figure 4 is a vertical sectional view through one of the traction members, and

Figure 5 is a vertical sectional view taken substantially on line 5—5 of Figure 4.

Referring to the drawings for a more detailed description thereof, wherein the several figures illustrate the preferred embodiment of the invention, the marking device generally indicated by the reference numeral 10 includes a substantially rectangular shaped frame 11 having parallel spaced supporting top members 12 and side members 13. The side members 13 are cut out

as indicated at 14 for reducing the weight of the device and said side members are adapted to support in spaced relation a pair of threaded shafts 15 attached thereto by nuts or other fastening means 16.

It is preferred that the marking device 10 be also capable of supporting the paint and other spraying mechanism required for marking the road surface and that the same be removably associated with the frame 11. As shown in Figure 1 of the drawings a paint container 17, pump 18 and conventional compressor type engine 19, are mounted upon a flat tray-like member 20 which member is supported upon the parallel extending top members 12. The spraying mechanism generally designated by the numeral 21 may be of conventional form including a pressure nozzle 22 having communication through a valve controlled line 23 with the container 17, compressed air being fed to the nozzle 22 through a line 24 connected with the pump 18. In this type of spray mechanism, paint is fed from the container to the nozzle by a siphoning action and is ejected from the nozzle by the compressed air. It is to be understood that one or more nozzles 22 may be employed which would be required when painting a relatively wide stripe. The nozzle or multiplicity of nozzles 22 are suspended on a bracket 25 so as to be disposed between the pair of traction members 26 and 27, which members 30 will be hereinafter more fully described.

Referring more particularly to Figure 3 of the drawings, it will be noted that the pair of traction members 26 and 27 are disposed between the side walls 13 of the frame 11 and extend beyond each end thereof. The traction members 26 and 27 are identical in construction in that they comprise inner and outer plates 28 and 29, respectively, mounted on the threaded shafts 15 through the medium of the collar 30. Each of the plates is substantially oval-shaped and form tread carrying members that are adjustably supported on the respective shafts 15. An annular rim 31 and 32 is secured by any desired members to the plates 28 and 29, respectively, for supporting therebetween a series of spaced rollers 33 which rollers have a bearing portion 34 extending on each end thereof for reception in a corresponding sized opening formed in opposed sides of the rims 31 and 32. An endless rubber tread member 35 is supported on the rollers 33 and projects slightly beyond the plates 28 and 29 for engagement with the surface of the road, pavement or the like. By this construction, it will be seen that a caterpillar-like traction means is pro-

vided for conveying the device along a roadway, pavement or the like to be marked.

An annular groove 36 is formed on the inner portion of the tread member 35 for receiving the 5 inwardly bent upper end 37 of the inner plate 28 for preventing any paint which may be sprayed along the sides of the tread member from entering between the plates and coming in contact with the spaced rollers 33. The lower end 38 of 10 the inner plate 28 extends parallel to the outer plate 29 as more clearly shown in Figure 4 of the drawings.

As is to be understood, the space 39 between the 15 traction members 26 and 27 constitutes the width of the stripe or mark to be painted on the road or pavement surface and the spraying nozzles 22 are disposed within said space. Means is provided for adjusting the relation of the traction members 26 and 27 on the respective shafts 15 20 to vary the width of the space 39. In Figure 4 of the drawings, it will be noted that the spaced plates 28 and 29 are fixedly held on the threaded shaft 15 through the medium of nuts or the like 40, and when desiring to adjust the width of the 25 space between the traction members 26 and 27, the retaining nuts 40 are loosened and the entire assembly of each traction member moved toward or away from each other on the shafts 15. When the proper spacing has been obtained, 30 said members are again secured to the shafts 15 by tightening the nuts 40.

In view of the fact that paint is sprayed from the nozzle 22 between the pair of traction members 26 and 27, it is desirable to provide a splash 35 plate 41 removably supported on hook-shaped members 42 on the lower end of the plate 28. The splash plate 41 is readily removed for cleaning thus protecting the inner plate 28 from contact with the paint.

40 Any residue of paint accumulating on the tread member 35 will be removed therefrom by a scraper 43 attached at 44 to the frame 11. It is only necessary for the scraper 43 to contact the inner edge of the tread member since that is the only 45 portion which comes in contact with the spraying paint.

Any desired means may be employed for moving the device over a roadway or other surface being marked, such as a self-contained driving 50 unit. As shown in the drawings, however, the device is adapted to be manually pushed through the handle 45 extending from the frame 11. In use of the device, the traction members 26 and 27 are first set for the desired width of stripe or 55 mark to be painted. The spraying mechanism is then operated and while moving the device along the surface, the paint will be discharged from the nozzle 22 and paint a stripe the exact width of the space between the traction members. During 60 the movement of the device over the surface, the tread members 35 will be revolved caterpillar fashion over the rollers 33. Means for controlling the spraying mechanism 21 may be disposed on the handle or otherwise conveniently located 65 so that the device would only require one person to operate it.

If desired, the tread member 35 can be formed of two sections so that the inner portion 46, which receives the greater percentage of wear 70 can be replaced without replacing the entire tread. It is also to be understood that the tread 35 may be formed of a single unit of material.

Also it will be understood, of course, by those skilled in the art that variations in the hereinabove described device involving the substitution

of substantial equivalents for the devices described are intended to be comprehended within the spirit of the present invention and that the invention is capable of extended application and is not confined to the exact showing of the drawings nor to the precise construction described and, therefore, such changes and modifications may be made therein as do not affect the spirit of the invention nor exceed the scope thereof as expressed in the appended claims.

What is claimed is:

1. A marking device comprising, in combination, a pair of shafts supported in a frame, a pair of parallel spaced tread carrying members mounted on said shafts, rollers carried by said members and arranged in spaced relation around the peripheries thereof, endless rubber tread members mounted on said rollers and engageable with a road surface, and a paint spray mechanism arranged to deliver a spray of paint 20 upon the surface of the road between said tread carrying members.

2. A marking device comprising, in combination, a pair of shafts supported in a frame, a pair of parallel spaced tread carrying members supported on said shafts and having rollers mounted in spaced relation around their peripheries, endless rubber tread members mounted on said rollers and engageable with a road surface, said endless tread members having a groove formed 25 on the inner surface thereof for engagement with the upper edge of one of said members, and a paint spray mechanism arranged to deliver a spray of paint upon the surface of the road between said tread carrying members.

3. A marking device comprising, in combination, a pair of threaded shafts supported in a frame, a pair of parallel spaced tread carrying members adjustably supported on the shafts and having rollers mounted in spaced relation around their peripheries, endless rubber tread members mounted on said rollers and engageable with a road surface, and a paint spray mechanism supported on said frame and adapted to deliver a spray of paint on the surface of the road between 30 said tread carrying members.

4. A marking device comprising, in combination, a pair of threaded shafts supported in a frame, a pair of parallel spaced tread carrying members adjustably supported on said shafts, rollers mounted in spaced relation about the peripheries of said members, endless rubber tread members frictionally engaging said rollers, said endless tread members having a groove formed on the inner surface thereof for attachment with the inner of said spaced members, a splash plate 40 removably attached to the inner of said members, and paint spray mechanism supported on said frame and arranged to deliver a spray of paint upon the surface of the road between said 45 tread carrying members.

5. A marking device comprising, in combination, a frame, a pair of threaded shafts supported in said frame, a pair of inner and outer oval-shaped tread carrying members adjustably supported in spaced relation on said shafts, rollers mounted in spaced relation about the peripheries of said members, endless rubber tread members frictionally engaging said rollers and supported between each pair of members, said 55 endless tread members having a groove formed on the inner surface thereof for attachment with the upper end of said inner spaced members, and paint spraying mechanism supported on said frame and arranged to deliver a spray of paint 60 upon the surface of the road between said tread carrying members.

on the surface of the road between said tread carrying members.

6. A marking device, comprising, in combination, a pair of shafts supported in a frame, a pair of parallel spaced tread carrying members supported on said shafts, rollers mounted in spaced relation about the peripheries of said members, endless rubber tread members frictionally en-

gaging said rollers, a splash plate removably attached to the inner of said members and a paint spray mechanism supported on said frame and arranged to deliver a spray of paint on the surface of the road between said tread carrying members. 5

ALBERT L. LUNDQUIST.
